Primary Examiner — Brian N. Vinson(74) *Attorney, Agent, or Firm* — KPPB LLP**CLAIM**

The ornamental design for a filament-style LED array light, as shown and described.

DESCRIPTION

FIG. 1 is a front elevation view of a filament-style LED array light, according to an embodiment of the invention.

FIG. 2 is a top plan view of the embodiment.

FIG. 3 is a bottom plan view of the embodiment; and,

FIG. 4 is a perspective view of the embodiment.

The features shown in broken lines do not form part of the claimed design.
